UNITED STATES PATENT OFFICE.

JOHN TALBERT, OF SIMSBOROUGH, LOUISIANA, ASSIGNOR OF ONE-HALF TO
FRANKLIN D. TALBERT, OF SAME PLACE.

APPARATUS FOR HOLDING BOLTS OF CLOTH.

SPECIFICATION forming part of Letters Patent No. 425,011, dated April 8, 1890.

Application filed July 8, 1889. Serial No. 316,872. (No model.)

To all whom it may concern:

Be it known that I, JOHN TALBERT, a citizen of the United States, residing at Simsborough, in the parish of Lincoln and State 5 of Louisiana, have invented a new and useful Machine for Holding Bolts of Cloth, &c., of which the following is a specification.

This invention has relation to a holder for supporting rolls or bolts of bagging, cloth, or 10 other material handled in large bolts during the operation of cutting the same into lengths for any purpose whatever; and among the objects in view are to provide a cheap and simple holder adapted to readily receive a 15 bolt or roll of goods and to maintain the same in proper position so as to be withdrawn from the holder evenly, and to provide means whereby the tumbling or rolling of the bolt or roll will not be impeded by frictional contact with the holder.

With the above general objects in view the invention consists in certain features of construction hereinafter specified, and particularly pointed out in the claims.

25 Referring to the drawings, Figure 1 is a perspective of a roll support or holder constructed in accordance with my invention. Fig. 2 is an end view. Fig. 3 is a transverse section. Fig. 4 is a detail in longitudinal section of one of the sides.

Like numerals of reference indicate like parts in all the figures of the drawings.

In practicing my invention I provide two opposite **U**-shaped sides, each consisting of two 35 **U**-shaped sections 1, spaced apart by means of space-blocks 2, and journaled between said sections is a series of friction-rollers 3 upon spindles 4, passing through the sections of each side. A pair of legs, as 5, are secured 40 between each pair of sections, and opposite tie-bars 6 extend across the front and rear pairs of legs, for the purpose of maintaining the same in proper relation with each other. One of the upper ends of the sides are connected by a guide-rod 7.

45 8 represents opposite cleats having registering perforations or bearings 9, in which are journaled a series of longitudinally-disposed rollers 10, said rollers being nearly flush 50 with the inner edges of the curved sides. Projecting from each of the sides are **L**-shaped

guides 11, the same being preferably adjustable to and from its respective side, whereby the device is adapted for the accommodation of goods of different widths.

55

The operation of my invention is as follows: A roll of goods is placed in the holder and extends from one side to the opposite, and the guides 11 are adjusted so as to prevent any great amount of lateral motion of the goods 60 during the operation of unwinding the same. The leading end of the roll is then drawn over the rod 7, and by further drawing upon the same any amount of goods may be taken from the roll in desired quantities, said roll 65 in the meantime revolving within the holder upon the friction-pulleys and bars or rolls described.

By the above construction it will be seen that I provide a holder adapted to receive 70 goods regardless of the manner in which they may be rolled or put up for the market, which holder obviates any liability of the goods being delivered crooked from the roll or unduly stretched by catching in objects, and also ac- 75 complish this in a small space.

If desired, the sides formed by the sections 1 may be cast integrally and made of metal, I not limiting my invention to minor details of construction.

80

Having described my invention, what I claim is—

1. In a holder of the class described, the combination, with the opposite connected **U**-shaped sides and a series of friction-rollers 85 journaled therein and having their peripheries projecting slightly above the inner periphery of the sides, of a transverse cloth-guiding bar connecting the ends of the sides, and a suitable support for the sides, substan- 90 tially as specified.

2. In a holder for the purpose specified, the opposite pairs of **U**-shaped sections forming opposite sides, the sides and sections being suitably connected to each other, in combina- 95 tion with a series of rollers journaled between each pair of sections, and a guide-bar connecting two adjacent ends of the sides, sub- substantially as specified.

3. In a holder of the class described, oppo- 100 site **U**-shaped sides mounted upon suitable legs and provided with an upper guiding-bar

- extending from the end of one side to the other, and with opposite cleats having bearings and a series of rollers arranged in the bearings, substantially as specified.
5. The herein-described holder formed of opposite sides supported on legs, each of which sides consists of a pair of **U**-shaped sections spaced apart and bolted together, and small friction-rollers mounted in the space between the sections, as set forth. 15 20
4. The herein-described holder formed of opposite sides, each of which consists of a pair of **U**-shaped sections spaced apart and bolted together, rollers mounted in the sections, and rollers extending from one side to the other, legs for supporting each side, a guide-bar extending from one side to the other, and **L**-shaped gages connected with each side and projecting laterally therefrom, substantially as specified.

In testimony that I claim the foregoing as my own I have hereto affixed my signature in presence of two witnesses.

JOHN TALBERT.
